US00D941609S

(12) **United States Design Patent** (10) **Patent No.:** **US D941,609 S**
(45) **Date of Patent:** **** Jan. 25, 2022**

(54) **NECK PILLOW**

(71) Applicant: **Chengdu Gyson Technology Inc.**,
Chengdu (CN)

(72) Inventor: **Yu Peng**, Chengdu (CN)

(**) Term: **15 Years**

(21) Appl. No.: **29/757,659**

(22) Filed: **Nov. 9, 2020**

(30) **Foreign Application Priority Data**

Sep. 21, 2020 (CN) 202030561879.3
